UNITED STATES PATENT OFFICE.

HENRY M. COSEY, OF FLINT, MICHIGAN.

SWITCH-OPERATING MECHANISM.

1,350,786.

Specification of Letters Patent. Patented Aug. 24, 1920.

Application filed November 13, 1919. Serial No. 337,779.

To all whom it may concern:

Be it known that I, HENRY M. COSEY, a citizen of the United States, residing at Flint, county of Genesee, State of Michigan, have invented a certain new and useful Improvement in Switch-Operating Mechanism, and declare the following to be a full, clear, and exact description of the same, such as will enable others skilled in the art to which it pertains to make and use the same, reference being had to the accompanying drawings, which form a part of this specification.

This invention relates to switch operating mechanism, and has for its object an improved organization of parts by means of which a switch can be thrown so as to open either the main track or the siding to an approaching car, without the necessity of either maintaining an operator on duty to throw the switch point with a hand bar or by means of a fixed switch lever, and without having to stop the car. No reliance is placed upon electricity for this purpose, and the throwing of the switch can be accomplished by the motorman or engineer of the car, from his platform thereon.

In the drawings:

Figure 1 is a perspective of my improved mechanism in position relatively to a switch and the adjacent track rails.

Fig. 2 is a plan view from above.

Fig. 3 is an enlarged detail of the pivoted contact spanner and of its actuating gear wheel, in the relative positions that they occupy when switch is closed.

Fig. 4 is a view similar to Fig. 3, with the parts occupying the positions held by them when the switch is open.

Fig. 5 is a sectional elevation along the line 5-5 of Fig. 4.

Fig. 6 is a detail elevational view through the center of the guide slot into which the contact wheel projects.

Fig. 7 is an enlarged detail view of the gear wheel.

Fig. 8 is an enlarged detail view of contact spanner.

Fig. 9 is a view of the L-shaped lever by which the movement of the contact spanner is transmitted to the switch point.

Fig. 10 is a side elevational view of the tripping lever suspended beneath the car platform.

A and B represent a pair of parallel rails of a track, the fixed frog C being a con-

tinuation of the rail A while the position of the pivoted frog D determines whether the car wheel passing over it shall continue on the main rail B or be diverted to the 60 branch or siding track E.

Extending transversely of the track from the pivoted frog D is a link F, whose other end is connected with one end of the pivoted angular lever L, which rests upon the 65 block G; from the other branch of the lever L, extends the link H, which is connected with the lower end of the Y-shaped contact lever J, which is pivoted as at K in the base I, which is located considerably nearer the 70 rail A than to the rail B. Pivoted on this block I between the branches M and N of the contact lever J is a two layered or compound gear or contact wheel P, composed of a top layer having sprocket teeth 75 Q, and a lower portion R whose branches are arranged in cruciform or four-leafed clover design.

The branches M and N of the contact lever J are of such thickness as to pass under 80 the sprocketed portion of the gear wheel, but they lie in the same plane as the cruciform portion R and are adapted to have the adjacent inner faces of their outer ends engaged by the rounded ends of these cruciform contact pieces as the whole gear wheel 85 P turns.

This gear or contact wheel P is pivoted in such position that as it turns its sprocket teeth Q just extend into the vertical plane 90 of the slot T, which forms a narrowed extension of the guide groove S, both of which are located in the plate W and extend parallel to the adjacent rail A. The open or entrance end of the guide groove is curved 95 downwardly from the exposed surface of the plate W, as shown particularly in Figs. 1 and 6, to facilitate the easy and comparatively gradual dropping thereinto of the actuating finger or rod V carried on the car. 100 In Fig. 10 I have shown this rod V as of a slightly bent over or hooked form, yieldingly suspended as by the spring U from a car platform X and adapted to be forced downwardly, against the pull of the spring 105 U by pressure of the motorman's foot upon the stem Y. I do not however, desire to be understood as restricting myself to this particular embodiment of the actuating mechanism.

With whatever form of actuating finger 110 may be used, it is obvious that as the finger

or rod is drawn through the guide groove S and slot T, it engages one of the sprocket teeth Q and throws the entire wheel P around through an arc of sufficient size to bring one of the arms of the cruciform projection R underneath into sharp engagement with the tip of the branch M of the contact lever J; this latter being pivoted at K, the sharp throw of the lever is communicated through the link H, crooked lever L and link F to the pivoted frog D, pulling the same to such position that the main track is closed and the siding track is open. If the next car to pass that way is also to follow onto the siding, no actuation of the switch is necessary, but if it is to follow the main track, the lowering of the actuating finger V into the groove S and slot T against one of the sprocket teeth Q once more, causes a turn of the gear wheel P, this time so that one of the projections R engages the other branch N of the contact lever J, which, acting through the link H, lever L and link F, once more throws the pivoted frog D so as to close the siding track and leave the main track B open.

What I claim is:

1. In combination with main line and siding rails, a pivoted switch tongue operably located with respect thereto, a rotatable gear wheel located in substantially the same horizontal plane as said rails and said switch tongue, in position to be rotatively actuated by the end of an actuating bar supported from a car, a pivoted yoke piece, one or the other of whose oppositely located tip portions are adapted to be engaged by a projecting portion of said gear wheel when the same is actuated, and link and lever members operatively connecting said pivoted switch tongue and said yoke piece, thereby transmitting to said pivoted frog piece from said gear wheel the actuation due to the engagement of the latter by the suspended actuating bar.

2. The combination, with a pivoted switch tongue and track rails, of a rotatable gear wheel adapted to be successively actuated through an arc of predetermined size by the engagement, each time a car passes therover, of an actuating bar depending therefrom, a bifurcated lever member pivotally anchored in position for one or the other of its opposing end portions to be engaged by

a projecting portion of said gear wheel when rotated, and link and lever members operatively connecting said switch tongue and said bifurcated lever member, whereby movement of said gear wheel when actuated is transmitted to said pivoted switch tongue.

3. In combination with a main track and a siding track, a tongue member operatively associated therewith, a bifurcated lever member operatively connected with said tongue member, a rotatable gear wheel adapted to engage with one of its projecting portions one or the other of the adjacent ends of said bifurcated lever member when actuated by the engagement against it of a rod depending from a car traversing said track, and a guideway into and through which the actuating rod passes before encountering said rotatable gear wheel.

4. The combination of a main track, a siding track, switch tongue members for operatively connecting the same, a bifurcated lever member operatively connected with said switch tongue members, and a rotatably anchored gear wheel about which the bifurcated end portions of said lever member partially engage, adapted to be actuated through an arc of predetermined size by the engagement thereagainst of a bar suspended from a car traversing said track, thereby sharply contacting one or the other of the bifurcated ends of said lever, and in turn causing the actuation of said switch tongue members accordingly.

5. The combination, with a main track, of a fixed and a pivoted tongue member whereby a siding track is placed in connection therewith, a bifurcated lever member operatively connected with said pivoted tongue member, and a rotatable gear wheel located between the branching portions of said lever member in position to be tripped by a car passing along said track, adapted to sharply engage one or the other of said bifurcated portions of said lever members, thereby actuating through it said pivoted tongue member.

In testimony whereof, I sign this specification in the presence of two witnesses.

HENRY M. COSEY.
